CAR ROOF

Filed July 11, 1930

UNITED STATES PATENT OFFICE

CHARLES DAVID BONSALL, OF PITTSBURGH, PENNSYLVANIA, ASSIGNOR TO P. H. MURPHY COMPANY, OF NEW KENSINGTON, PENNSYLVANIA, A CORPORATION OF PENNSYLVANIA

CAR ROOF

Application filed July 11, 1930. Serial No. 467,261.

This invention relates to metal car roofs of the type wherein the metal roof sheets are provided along their adjacent margins with raised panels and are connected by weatherproofing seam caps having outstanding base flanges that rest on said raised panels. The principal object of the present invention is to provide for maintaining the raised marginal panels of the sheets in contact with the base flanges of the seam caps and thereby increase the weatherproofing qualities of the roof. Other objects are simplicity and cheapness of construction, fewness of parts and ease of assembly. The invention consists in the parts and in the combinations and arrangements of parts hereinafter described and claimed.

In the accompanying drawings, which forms part of this specification and wherein like symbols refer to like parts wherever they occur,

Fig. 1 is a plan view of a portion of the car roof embodying my invention,

Fig. 2 is an enlarged transverse cross-section through one-half of the roof, on the line 2—2 of Fig. 1,

Figs. 3 and 4 are transverse cross-sections through a roof seam and the carline located therebelow on the lines 3—3 and 4—4, respectively, in Fig. 2; and

Fig. 5 is a plan view of one of the bolt supporting straps.

Referring to the accompanying drawings, my invention is shown in connection with a car roof frame or substructure comprising Z-bar side plates A connected by channel-shaped carlines B having outstanding flanges 1 at the tops of their side walls. The Z-bar side plates A are arranged with their webs horizontal and with one flange in and extending upwardly; and the ends of the carlines B are rigidly secured to the respective side plates by means of carline brackets C that have channel-shaped body portions adapted to receive the ends of said carlines and depending end flanges that are riveted flatwise to the upstanding inner flanges of said side plates.

Metal roof sheets D extend from side to side of the car between carlines with their eaves end portions supported on wooden fas-

cia strips E that are removably secured flatwise to the outer faces of the upstanding inner flanges of the side plates. The roof sheets D are provided with depending eaves flanges 2 that overhang the outer edges of the fascia strips and terminate at their eaves ends in in-turned flanges that are spaced away from said fascia strips, whereby said sheets are independently movable. The roof sheets D are spaced apart along their adjacent side margins, which are offset upwardly above the carlines, forming raised panels 3 at the sides of the sheets. The raised side panels 3 of the roof sheets extend from end to end thereof and the free marginal edges of said panels are bent up to form upstanding flanges 4 at the side marginal edges of the sheets. Throughout the greater portion of their length, the side marginal flanges 4 of the roof sheets are of substantially uniform depths, but the end portions of said flanges slope downwardly toward the plane of the sheets adjacent to the eaves end thereof.

The roof sheets D are spaced apart on opposite sides of the longitudinal center lines of the carlines with their raised side marginal panels 3 spaced above the outstanding top flanges of said carlines. The roof sheets are loosely connected along their adjacent side margins by weatherproofing seam caps F of substantially inverted channel-shaped section which extend from eaves to eaves of the car and are provided at the lower edges of their side walls with outstanding base flanges 5 that rest on the raised side marginal panels 3 of adjacent sheets. The seam caps F are provided at their eaves ends with depending flanges 6 that overhang and are spaced from the eaves corners of adjacent roof sheets and terminate at their lower ends in in-turned flanges which extend beneath and are spaced below the in-turned lower ends of the depending eaves flanges 2 of said roof sheets. The seam caps F are preferably made in three sections; namely, duplicate end sections 7, which extend from eaves to points adjacent to the ridge, and a ridge or intermediate section 8, which overlaps the ridge end portions of the two end sections for a suitable distance on each side of the ridge.

In order to prevent the raised side marginal panels 3 of the roof sheets D from springing away from the base flanges 5 of the seam caps F and thus causing the roof to leak, said panels are supported on wooden filler strips 9 that rest on the carlines B and extend longitudinally thereof from side plate to side plate. The wooden filler strips 9, which are of a thickness corresponding to distance between the carlines and raised panels of the roof sheets, cover the channels in the carlines, and are secured to the outstanding top flanges thereof preferably by means of bolts 10.

The seam caps F are held down on raised panels of the sheets and said panels are, in turn, held down on the wooden filler strips by means of upright bolts G located adjacent to the ridge and eaves of the car. Each of said bolts is supported at its lower end on a strap 11 disposed transversely of the carline with its ends rigidly secured in depressions 1a provided therefor in the outstanding top flanges 1 of the carline. The portion of the strap that spans the channel of the carline is provided with a vertical hole adapted to loosely receive the threaded lower end of the bolt. Each bolt is secured to the depressed portion of its supporting strap by means of nuts 12 and 13 that are threaded on the bolt in position to bear against the top and bottom faces of said strap. Each bolt extends upwardly through a hole 9a provided therefor in the filler strip 9 and is provided near its upper end with a collar 14 forming a shoulder adapted to support the web of the seam cap; and the portion of the bolt located above said collar extends through an opening in said web and is threaded to receive a nut 15 which serves to clamp said cap to said shoulder. The bolt receiving portion of the strap is offset downwardly in the channel of the carline so that any water that runs down the bolt will be prevented from entering the car over the sides of the carlines. In assembling the parts, the upper nut 12 is threaded on the bolt whose threaded lower end is extended downwardly through the opening in the depressed middle portion of the strap, after which the lower nut 13 is tightened to firmly clamp the bolt to the strap.

Running boards 16 extend longitudinally of the car at their ridge and are supported on and secured to the lateral top flanges of Z-bar running board saddles 17, whose lateral base flanges rest on the ridge sections 8 of the seam caps F and are rigidly secured thereto by the bolts which secure the ridge portions of said seam caps to the carlines.

By the arrangement described, the raised panels of the roof sheets serve to locate the joints between the sheets and the seam caps above the general drainage level of the sheets and thus overcomes the tendency for the water to lodge in said joints and produce rust.

Leakage between said joints is further pre-

vented by means of the filler strips which firmly support the raised panels of the sheet throughout their length and thus prevent said panels from sagging or springing away from the base flanges of the seam caps. 70

The invention is not limited to the precise construction of seam and car substructure shown and described.

What I claim is:

1. A car roof comprising a substructure having frame members, roof sheets spanning from frame member to frame member and provided along their adjacent margins with raised panels located above said frame members, members interposed between the tops of said frame members and the raised marginal panels of the roof sheets for supporting said panels, seam caps connecting adjacent sheets and having base flanges resting on the raised marginal panels thereof, and connections between the said frame members and seam caps for holding the raised marginal panels of the roof sheets down on said supports and the base flanges of the seam caps down on said raised panels. 75 80 85 90 95

2. A car comprising a substructure having frame members of substantially channel-shaped cross-section, roof sheets spanning from frame member to frame member and provided along their adjacent margins with raised panels located above said frame members, members interposed between the tops of said frame members and the raised marginal panels of the roof sheets for supporting said panels, the channels in said frame members opening upwardly and being covered by the panel supporting members, seam caps connecting adjacent sheets and having base flanges resting on the raised marginal panels thereof, and connections between the said frame members and seam caps for holding the raised marginal panels of the roof sheets down on said supports and the base flanges of the seam caps down on said raised panels. 100 105 110

3. A car comprising a substructure having frame members of substantially channel-shaped cross-section, roof sheets spanning from frame member to frame member and provided along their adjacent margins with raised panels located above said frame members, members interposed between the tops of said frame members and the raised marginal panels of the roof sheets for supporting said panels, the channels in said frame members opening upwardly and being covered by the panel supporting members, seam caps connecting adjacent sheets and having base flanges resting on the raised marginal panels thereof, and connections between the said frame members and seam caps for holding the raised marginal panels of the roof sheets down on said supports and the base flanges of the seam caps down on said raised panels, said connections comprising upright bolts having their lower ends secured in the chan- 115 120 125 130

nels of said frame members and their upper ends secured to said seam caps.

4. A car roof comprising side plates, carlines connecting said side plates, roof sheets extending transversely of the car between carlines and provided along their adjacent side margins with raised panels located above said carlines, means interposed between the carlines and the raised side marginal panels of the roof sheets for supporting said panels, seam covers connecting adjacent sheets and having base flanges resting on the raised marginal panels thereof, and connections between the carlines and seam covers for holding the raised side marginal panels of the roof sheets down on the supports and the base flanges of the seam covers down on said raised panels.

5. A car roof comprising side plates, carlines connecting said side plates, said carlines being of substantially channel-shaped cross-section with outstanding flanges at the tops of their side walls, roof sheets extending transversely of the car between carlines and provided along their adjacent side margins with raised panels located above the top flanges of said carlines, filler strips interposed between the top flanges of said carlines and the raised side marginal panels of the roof sheets for supporting said panels, seam caps connecting adjacent sheets and having base flanges resting on the raised marginal panels thereof, and connections between said carlines and seam caps for holding the raised side marginal panels of the roof sheets down on the filler strips and the base flanges of the seam caps down on said raised panels.

6. A car roof comprising side plates, carlines connecting said side plates, said carlines being of substantially channel-shaped cross-section with outstanding flanges at the tops of their side walls, roof sheets extending transversely of the car between carlines and provided along their adjacent side margins with raised panels located above the top flanges of said carlines, filler strips interposed between the top flanges of said carlines and the raised side marginal panels of the roof sheets for supporting said panels, seam caps connecting adjacent sheets and having base flanges resting on the raised marginal panels thereof, and connections between said carlines and seam caps for holding the raised side marginal panels of the roof sheets down on the filler strips and the base flanges of the seam caps down on said raised panels, said connections comprising upright bolts having their upper ends removably secured to said seam covers and their lower ends adjustably secured to said carlines.

7. A car roof comprising side plates, carlines connecting said side plates, said carlines being of substantially channel-shaped

cross-section with outstanding flanges at the tops of their side walls, roof sheets extending transversely of the car between carlines and provided along their adjacent side margins with raised panels located above said carlines, wooden filler strips interposed between the carlines and the raised side marginal panels of the roof sheets for supporting said panels, seam caps connecting adjacent sheets and having base flanges resting on the raised marginal panels thereof, straps extending transversely of said carlines across the tops thereof, upright bolts adjustably supported at their lower ends on said straps, and nuts on the upper end of said bolts for securing the seam caps thereto.

8. A car roof comprising side plates, carlines connecting said side plates, said carlines being of substantially channel-shaped cross-section with outstanding flanges at the tops of their side walls, roof sheets extending transversely of the car between carlines and provided along their adjacent side margins with raised panels located above the outstanding top flanges of said carlines, filler strips interposed between the carlines and raised side marginal panels of the roof sheets for supporting said panels, inverted channel-shaped seam caps loosely connecting adjacent sheets and having base flanges resting on the raised marginal panels thereof, straps extending across the tops of the carlines with their ends secured to the top flanges thereof, upright bolts having threaded lower ends extending through openings provided therefor in said straps, nuts threaded on said lower portions of said bolts and adapted to bear against the top and bottom surfaces of said straps, the upper portions of said bolts being threaded and extending through openings provided therefor in the tops of said seam caps, said bolts being provided below the tops of said caps with shoulders, and nuts on the upper ends of said bolts for clamping the tops of said seam caps to said shoulders.

9. A car roof comprising a substructure having frame members, roof sheets spanning from frame member to frame member with their adjacent margins spaced above said frame members, members interposed between the tops of said frame members and the margins of the roof sheets for supporting said margins, seam caps connecting adjacent sheets and having base flanges resting on the margins thereof, and connections between said frame members and the seam caps for holding the margins of the roof sheets down on said supports and the base flanges of the seam caps down on said margins.
